UNITED STATES PATENT OFFICE

2,466,031

JIG

Luigi Luisi, New York, N. Y.

Application July 23, 1947, Serial No. 763,126

6 Claims. (Cl. 77—62)

(Granted under the act of March 3, 1883, as
amended April 30, 1928; 370 O. G. 757)

1

This invention relates to improvements in jigs, and more particularly pertains to improvements in jigs adapted to secure machine bolts and the like for drilling transverse bores therein, and to position a drill for such operation.

In drilling transversely through the head or the threaded portion of a bolt, for the purpose of inserting a safety wire, cotter pin or the like therethrough, it has been common practice to lay out each workpiece and drill on a V-block support, or to construct a rudimentary jig adapted to handle a particular size of bolt. These methods, however, are wasteful of time and material, do not produce uniformly accurate results, and do not permit duplication of work on a production basis.

The primary object of this invention is to provide a jig of simple and durable construction adapted to secure a machine bolt or the like for drilling transverse bores therein and to guide a drill for the performance of such operation.

Another object is to provide a jig of the character described adapted to accommodate a range of sizes of workpieces.

Still another object is to provide a jig of the character described wherein a workpiece can be secured readily and facilely.

A further object is to provide a jig of the character described including a drill bushing adapted to be aligned normal to a workpiece.

Further objects and advantages of this invention, as well as its construction, arrangement and operation, will be apparent from the following description and claims in connection with the accompanying drawing, in which

Fig. 1 is an isometric view of a jig, partly broken away, showing a preferred embodiment of the invention;

Fig. 2 is an isometric view of an adjustable seat element of said jig; and

Fig. 3 is an isometric view of a modified form of seat element thereof.

Similar numerals refer to similar parts throughout the several views.

A base plate 11 carries a first upright 13 adjacent one end of said base plate and a second upright 15 adjacent the opposite end of said base plate and parallel to said first upright. Each of said uprights defines substantially a right triangle in elevation, to facilitate manipulation of a workpiece in the hereinafter described discs thereof. Upright 13 is provided with a dome lug 17 protruding from the medial portion of the edge of the hypotenuse thereof, and upright 15 is provided with a similar and similarly disposed dome lug 19, said dome lugs providing bearings for the

2

shaft hereinafter described. The external face of upright 13 is provided with a plurality of indexing pin bores 21 concentric the bearing of dome lug 17, and setscrew 23 extends into the bearing in dome lug 19 to provide means for securing said shaft against rectilinear movement.

Slot 25 in upright 13 is disposed normal to base plate 11, and similar slot 27 in upright 15 is disposed similarly. Arm 29 integral the end of upright 13 distal base plate 11 extends from said upright, being disposed in the elevation plane of said upright and parallel to the plane of said base. Similar arm 31 is disposed similarly upon upright 15. Each of said arms is provided with a transverse recess in the edge of said arms distal base plate 11 adapted to carry slidably a slide bar hereinafter described. Arm 29 is provided with a threaded bore that receives the adjusting screw of said slide bar, and thumbscrew 33 extends into arm 31 to furnish means for securing said adjusting screw against rectilinear movement.

Shaft 35, having key 37 disposed longitudinally thereon, is mounted rotatably and slidably in the bearings of dome lugs 17 and 19. Knob 39, secured 25 to said shaft external upright 13, is provided with an indexing pin 41 adapted to be seated in a selected indexing-pin bore 21 to secure said shaft against rotation in its bearings. Helical spring 43 bears against the butt disc 45 of said shaft and the external face of upright 15 to facilitate indexing of said shaft.

Disc 47, carried on hub 49, is mounted slidably on shaft 35, a suitable keyway in said disc and said hub being engaged by key 37 to prevent rotation of said disc relative shaft 35. Setscrew 51 in hub 49 is adapted to prevent rectilinear movement of disc 47 relative shaft 35. A plurality of bores 53, of a range of sizes, extend through disc 47, said bores being disposed in suitable spaced relation and preferably sequentially according to diameter. Radial slots 55 communicate between said bores 53 and the periphery of disc 47, the longitudinal center line of said slots intersecting the center of said bores. Preferably, the width of 40 each of said slots is somewhat less than the diameter of its associated bore, so that the side walls of said slots can serve as guides for a drill bushing hereinafter described.

Disc 57, carried on hub 59, is mounted slidably 50 on shaft 35, a suitable keyway in said disc and said hub being engaged by key 37 to prevent rotation of said disc relative shaft 35. Setscrew 61 in hub 59 is adapted to prevent rectilinear movement of disc 57 relative shaft 35. A plurality of bores 63, 55 of a range of sizes corresponding to the sizes of

bores 53, extend through disc 51, said bores 63 being disposed in correspondence relation with bores 53 of the same size, so that a workpiece can be positioned in selected bores 53 and 63 of the same size in axial parallelism with shaft 35. Flats 65 in the periphery of disc 51 are disposed normal to radii of said disc intersecting the center of said bores 63, and a plurality of setscrews 67 disposed on said radii extend from said flats to said bores 63, said setscrews being adapted to secure a workpiece positioned in said bores.

Slide bar 69 is seated slidably in the recesses of arms 29 and 31, lead screw 71 driven by hand wheel 73 being adapted to feed said slide bar rectilinearly; lead screw 71 is threaded through arm 29 and rotates in bearings in arm 31 and in arm 15 of slide bar 69. Longitudinal slots 71 and 79 in slide bar 69 carry thumb screws 81 and 83 respectively, thumb screw 81 being threaded into arm 29 and thumb screw 83 being threaded into arm 31 to function as means to secure said slide bar in selected position and as auxiliary guides therefor. Bore 85 in slide bar 69 extends therethrough between slots 71 and 79 normally to base 11, and carries drill bushing 87, which is secured removably therein. The longitudinal axis of bore 85 is positioned to intersect the longitudinal axis of shaft 35 throughout their respective ranges of movement.

A workpiece limit or stop assembly is carried slidably in slot 25 of upright 13. Said stop assembly includes a bar 89, a lug 91 mounted on a face of said bar and engaged slidably in slot 25, a thumbscrew 93 extending into said lug from the external face of upright 13 and adapted to secure said bar 89 against movement relative upright 13, and a threaded pin 95, adapted to be fed by rotation of head 97 and further adapted to be secured against such rotation by means of lock nut 99. Said pin 95 is threaded in bar 89, with said pin in axial parallelism with the shaft 35, the respective axes of said pin and said shaft lying in the same vertical plane, and the center of said pin being aligned with the centers of corresponding bores 53 and 63.

Seating element 101 is carried slidably in slot 27 of upright 15. As shown clearly in Fig. 2, said seating element comprises a block 103, a lug 105 mounted on a face of said block and adapted to be engaged slidably in slot 27, a thumbscrew 107 extending into the face of said lug distal block 103 and adapted to secure said block 103 against movement relative upright 15, and an integral offset plate 109.

The face of said plate 109 distal base plate 11 is adapted to seat the head of a workpiece, said face lying in a plane parallel to the face plane of base plate 11 and being intersected by a vertical plane including the longitudinal axis of shaft 35.

A modified form of seating element is shown in Fig. 3. Block 111 is provided with a lug 113 mounted on a face of said block and adapted to be engaged slidably in slot 27. Thumbscrew 115 extends into the face of said lug distal block 111 and is adapted to secure said block against movement relative upright 15. In lieu of the offset plate 109 shown in Fig. 2, there is provided an integral offset collar 117 having a plurality of spaced longitudinal slots adapted to engage the peripheral longitudinal keys 119 of an adapter pin 121, whereby a workpiece provided with a slotted head can be secured in desired position.

Various modifications and changes can be made in the subject device without departing from the scope of the invention.

The invention described herein may be manufactured and used by or for the Government of the United States of America for governmental purposes without the payment of any royalties thereon or therefor.

I claim:

1. A jig comprising a base plate, a first upright and a second upright extending from opposite ends of said base plate, a shaft mounted between said uprights, a first disc slidable rectilinearly on said shaft and rotatable on the axis of said shaft, means to secure said disc against such rectilinear movement, means to secure said disc against such rotation, a second disc slidable rectilinearly on said shaft and rotatable on the axis of said shaft, means to secure said disc against such rectilinear movement, means to secure said disc against such rotation, a plurality of bores of a range of sizes arranged in correspondence relation in said discs, radial slots communicating between the periphery and the bores of one of said discs, setscrews in the other of said discs communicating from the periphery to the bores thereof, a bar carried slidably between said uprights, means to move said bar rectilinearly, means to secure said bar in selected position, and a drill bushing mounted removably in said bar and adapted to be aligned with a selected radial slot.

2. A jig comprising a base plate, a first upright and a second upright extending from opposite ends of said base plate, a shaft mounted between said uprights, a first disc slidable rectilinearly on said shaft and rotatable on the axis of said shaft, means to secure said disc against such rectilinear movement, means to secure said disc against such rotation, a second disc slidable rectilinearly on said shaft and rotatable on the axis of said shaft, means to secure said disc against such rectilinear movement, means to secure said disc against such rotation, a plurality of bores of a range of sizes arranged in correspondence relation in said discs, radial slots communicating between the periphery and the bores of one of said discs, setscrews in the other of said discs communicating from the periphery to the bores thereof, a bar carried slidably between said uprights, means to move said bar rectilinearly, means to secure said bar in selected position, and a drill bushing mounted removably in said bar and adapted to be aligned with a selected radial slot, a stop mounted adjustably in one of said uprights and adapted to abut the end of a workpiece positioned in said bores, and a seating element mounted adjustably in the other of said uprights and adapted to provide a seat for the opposite end of said workpiece.

3. A jig comprising a base plate, a first upright and a second upright extending from opposite ends of said base plate, a shaft mounted rotatably and slidable rectilinearly between said uprights, means to secure said shaft against such rotation, means to secure said shaft against such rectilinear movement, a first disc slidable rectilinearly on said shaft, means to secure said disc against such rectilinear movement, a second disc slidable rectilinearly on said shaft, means to secure said disc against such rectilinear movement, a secopd disc slidable rectilinearly on said shaft, means to secure said second disc against such rectilinear movement, a plurality of bores of a range of sizes arranged in correspondence relation in said discs, radial slots communicating between the periphery and the bores of one of said discs, setscrews in the other of said discs communicat-

ing from the periphery to the bores thereof, and a drill bushing mounted adjustably between said uprights and adapted to be aligned with a selected radial slot.

4. A jig comprising a base plate, a first upright and a second upright extending from opposite ends of said base plate, a shaft mounted rotatably and slidably rectilinearly between said uprights, means to secure said shaft against such rotation, means to secure said shaft against such rectilinear movement, a disc slidably rectilinearly on said shaft, means to secure said disc against such rectilinear movement, a plurality of bores of a range of sizes arranged in correspondence relation in said disc, radial slots communicating between the periphery and the bores of said disc, setscrews in said disc communicating from the periphery to the bores thereof, a bar carried slidably between said uprights, means to move said bar rectilinearly, means to secure said bar in selected position, and a drill bushing mounted removably in said bar and adapted to be aligned with a selected radial slot.

5. A jig comprising a base plate, a first upright and a second upright extending from opposite ends of said base plate, a shaft mounted rotatably and slidably rectilinearly between said uprights, means to secure said shaft against such rotation, means to secure said shaft against such rectilinear movement, a first disc slidably rectilinearly on said shaft, means to secure said disc against such rectilinear movement, a second disc slidably rectilinearly on said shaft, means to secure said second disc against such rectilinear movement, a plurality of bores of a range of sizes arranged in correspondence relation in said discs, radial slots communicating between the periphery and the bores of one of said discs, setscrews in the other of said discs communicating from the periphery to the bores thereof, a bar carried slidably between said uprights, means to move said bar rectilinearly, means to secure said bar in selected position, and a drill bushing mounted re-

movably in said bar and adapted to be aligned with a selected radial slot.

6. A jig comprising a base plate, a first upright and a second upright extending from opposite ends of said base plate, a shaft mounted rotatably and slidably rectilinearly between said uprights, means to secure said shaft against such rotation, means to secure said shaft against such rectilinear movement, a first disc slidably rectilinearly on said shaft, means to secure said disc against such rectilinear movement, a second disc slidably rectilinearly on said shaft, means to secure said second disc against such rectilinear movement, a plurality of bores of a range of sizes arranged in correspondence relation in said discs, radial slots communicating between the periphery and the bores of one of said discs, setscrews in the other of said discs communicating from the periphery to the bores thereof, a bar carried slidably between said uprights, means to move said bar rectilinearly, means to secure said bar in selected position, and a drill bushing mounted removably in said bar and adapted to be aligned with a selected radial slot, a stop mounted adjustably in one of said uprights and adapted to abut the end of a workpiece positioned in said bores, and a seating element mounted adjustably in the other of said uprights and adapted to provide a seat for the opposite end of said workpiece.
